UNITED STATES PATENT OFFICE.

ALFRED FRESCHL, OF CHICAGO, ILLINOIS.

MEANS FOR SEALING BOXES, &c.

No. 816,007.

Specification of Letters Patent.

Patented March 27, 1906.

Application filed March 18, 1905. Serial No. 250,761.

To all whom it may concern:

Be it known that I, ALFRED FRESCHL, of Chicago, in the county of Cook, State of Illinois, have invented certain new and useful 5 Improvements in Means for Sealing Boxes or other Packages, of which the following is a specification.

This invention relates to improvements in means for sealing boxes or other packages 10 that are intended to be transported from one place to another; and the object of the improvement is to provide inexpensive means that can be applied to any ordinary shipping- 15 box, case, or package and which will furnish a seal therefor whereby any tampering with the box or package can only be accomplished by destroying the seal, and thus showing 20 that the box or package has been opened.

The invention consists generally in providing in the cover, sides, and bottom of a shipping box or package countersunk openings having recesses or indentations in its walls and a suitable sealing material placed in such countersunk openings and secured therein 25 by engagement with such recesses or indentations.

The invention consists, further, in the constructions and combinations hereinafter described, and particularly pointed out in the 30 claim.

In the accompanying drawings, forming part of this specification, Figure 1 is a transverse vertical section of a portion of a pack- 35 ing-box having my improved sealing means applied thereto. Fig. 2 is a similar view showing a modified form of the countersunk opening. Fig. 3 is another view showing the countersunk opening with indentations formed in its side walls. Fig. 4 is a section 40 on line 4-4 of Fig. 3. Fig. 5 is a plan view of the seal.

In all of the drawings, 2 represents a portion of the cover, side, or bottom of a box or shipping-case, which may be of any suitable 45 size and construction. The construction of the box or case will depend largely upon the use to which it is to be put, and it may be de- 50 sirable to apply the sealing means to the top, sides, and bottom, or to the top and bottom, or to the top alone, and I therefore do not limit myself in this application to the use of my sealing means in connection with any particular size or construction of shipping- 55 package.

In all of the drawings, 3 represents the side or end wall of the package to which the part

2 is to be secured. The part 2 is provided with a countersunk opening 4, and a screw or nail 5 is passed through the part 2, being ar- 60 ranged in the bottom of the recess 4 and en- 65 tering the part 3 of the case. The walls of the countersunk recess 4 are provided with recesses or indentations whereby a rough- 70 ened surface is formed. There may be a se- 75 ries of circular undercut recesses or indenta- 80 tions, as shown in Fig. 2, or a single circular recess, as shown in Fig. 1, or two or more in- 85 dentations of any suitable size and shape, as shown in Figs. 3 and 4 of the drawings. It 90 will be noted, however, that in all of these 95 forms the walls of the opening are provided with means for holding the sealing material in position.

In sealing the box or other package the 75 nails or screws are inserted through the part 2 into the part 3 and located in the bottoms of the openings 4, and a suitable sealing ma- 80 terial (preferably a material that can be put in place when plastic and which will harden after being so put in place) is filled into each 85 of the openings, covering the head of the screw or nail and entering the recesses or in- 90 dentations in the walls of the openings. Af- 95 ter the material is thus placed in the opening and while it is in plastic form a suitable im- 100 pression is made upon the surface of the plas- 105 tic material, so that this impression will ap- 110 pear in the surface of the sealing material when it becomes hard. With the sealing material engaging the recesses or indenta- 115 tions in the walls of the countersunk opening it will be permanently secured in place and 120 cannot drop out or be removed when it be- 125 comes dry and hard. As the sealing mate- 130 rial will usually shrink slightly as it becomes 135 hard, if it were not for these recesses or in- 140 dentations with which it engages there would 145 be danger that the sealing material would fall out or could be removed in an unbroken 150 state. By their use, however, I provide 155 means for permanently and effectually secur- 160 ing the sealing material in position.

When a box or case has been sealed by this 165 means, it may be shipped to any point, and upon arrival at its destination if the seals are 170 unbroken it will show conclusively that the 175 box or package has not been opened.

I do not limit myself to the details of the 180 construction of the sealing means, as it is ob- 185 vious that the same may be varied in many 190 particulars without departing from my inven- 195 tion.

I claim as my invention—

The combination, with the part 3 of a box or package, of the part 2 provided with a countersunk opening having recesses or indentations in its wall above the bottom and below the top of said opening, a suitable fastening device passing through the part 2 into the part 3 and having a head lying at the bottom of said opening, and suitable sealing material arranged in said opening to cover the head of the fastening and engaging the re-

cesses or indentations in its wall above said head and below the top of the part 2, substantially as described.

In testimony that I claim the foregoing as my invention I affix my signature, in presence of two subscribing witnesses, this 28th day of February, A. D. 1905.

ALFRED FRESCHL.
